UNITED STATES PATENT OFFICE.

THOMAS L. BURTON, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

BRAKE-BEAM AND HANGER-LEVER.

1,097,000.

Specification of Letters Patent.

Patented May 19, 1914.

Application filed August 27, 1913. Serial No. 786,839.

To all whom it may concern:

Be it known that I, THOMAS L. BURTON, a citizen of the United States, residing at Pittsburgh, in the county of Allegheny and State of Pennsylvania, have invented a certain new and useful Improvement in Brake-Beams and Hanger-Levers, of which improvement the following is a specification.

This invention relates to brake beams and hanger levers for supporting the same and the brake shoes, the object being to provide a simple construction which shall be interchangeable, and in which either the brake beam or the shoe may be pivotally attached at the lower end of the lever, and the other member at an intermediate point according as it may be desired to change the leverage of the hanger upon the brake shoe.

With this object in view, my improvement comprises a brake beam preferably of a rolled metal section, having bracket pieces attached at its ends and provided with slotted openings and pivot pins, whereby the hanger levers may be passed through said openings and pivoted to the beam either at the intermediate point of the hanger, in which case the brake shoe is pivotally mounted upon the lower end of the hanger, or the beam may be pivoted at the lower end of the lever, hanger, and the brake shoe be pivoted to the hanger at its intermediate point.

In the accompanying drawings: Figure 1 is a transverse section of the brake beam on the line 1—1 of Fig. 2, and showing the hanger lever and brake shoe in side elevation; Fig. 2, a plan of the brake beam; and, Fig. 3, a view similar to Fig. 1, but showing the brake beam and the brake shoe transposed as to their positions on the hanger lever.

According to the construction shown in the drawings, the brake beam, 5, is preferably formed of a rolled metal section, such as a channel, and at its ends are rigidly secured the brackets, 6, having slotted openings, 7, and pivot pins, 8. The openings are designed to admit the passage of the hanger

levers, 10, which may thus be pivoted on 50 the pins, 8, either at their lower ends, as indicated in Fig. 1, or at their intermediate points, as indicated in Fig. 3. In the first instance, the brake head and shoe, 11, is pivoted upon the hanger lever at the intermediate point, while in the latter case, it is 55 pivoted upon the lower end of the lever.

The brake beam is provided, preferably near its end, with lugs, 9, to which the truck levers or connecting rods of the truck brake 60 rigging may be pivotally attached.

It will thus be seen that the hanger levers are reversible, and the point of connection for the brake beams and shoes interchangeable, whereby the parts may be readily connected up to give the desired leverage 65 and pressure upon the brake shoes. Another advantage is that the hanger serves the function both as a hanger and as a truck lever, and but one set of parts need be carried in stock.

It will also be evident that, by means of my improvement, the brake head and shoe may be readily attached to, or detached from, the hanger lever without disconnecting any of the other parts, whether applied to the end of the lever, as shown in Fig. 3, or to the middle of the lever, as indicated in Fig. 1.

Having now described my invention, what 80 I claim as new and desire to secure by Letters Patent is:

1. The combination of a brake beam having slotted openings at its ends, hanger levers adapted to pass through said openings, 85 and means for pivoting the beam upon the levers either at its lower end or at an intermediate point.

2. The combination of a brake beam having brackets rigidly secured to its ends and 90 provided with slotted openings, hanger levers adapted to pass through said openings and adapted to be pivoted to said brackets either at the lower end or at an intermediate point of said levers, and brake shoes pivoted upon said levers, the points of attachment of the beams and of the brake shoes 95 upon the levers being interchangeable.

3. The combination of a brake beam having slotted openings at its ends, hanger levers adapted to pass through said openings, and means for pivoting the brake beams upon the levers at one point, and the brake shoes upon the levers at another point, the points of connection being interchangeable.

In testimony whereof I have hereunto set my hand.

THOMAS L. BURTON.
